UNITED STATES PATENT OFFICE.

THEODORE L. VALERIUS, OF WAUKEGAN, ILLINOIS, AND OLAF LARSEN, OF FORT ATKINSON, WISCONSIN, ASSIGNORS TO CREAMERY PACKAGE MFG. COMPANY, OF CHICAGO, ILLINOIS, A CORPORATION OF ILLINOIS.

HYDRAULIC CAN WASHER.

Application filed February 4, 1922. Serial No. 534,035.

To all whom it may concern:

Be it known that we, THEODORE L. VALERIUS and OLAF LARSEN, residing, respectively, at Waukegan, in the county of Lake 5 and State of Illinois, and at Fort Atkinson, in the county of Jefferson and State of Wisconsin, have invented certain new and useful Improvements in Hydraulic Can Washers, of which the following is a specification.

10 Our invention relates to mechanical washing apparatus and more specifically to an improved hydraulic can washer.

One object of our invention is to produce such an apparatus especially adapted to handle ice cream containers of all sizes as well 15 as covers for the same, and ice cream brick pans.

Another object is to eliminate rubbing between the parts of the machine and the containers going through the machine.

Another object is to carry the containers through the machine in a horizontal position.

An advantage of the construction we employ is that it is very easy to arrange it so as to prevent contamination between the different cleansing and sterilizing baths. Another advantage is that the mechanical parts may be so arranged as to be very easily 20 cleaned.

Further objects and advantages of our invention will become apparent as the description proceeds.

In the accompanying drawings, Fig. 1 is 25 a sectional plan view of a washing apparatus in which our invention has been embodied, shown as with the top wall of the machine removed.

Fig. 2 is a sectional elevation of the machine shown as with a side wall removed.

Fig. 3 is a cross sectional view taken on the vertical plane of the line 3—3 in Fig. 1.

Fig. 4 is a detailed sectional view taken on the plane of the line 4—4 in Fig. 2.

40 This application is a continuation in part of our previous application, Serial No. 409,172, filed Sept. 9th, 1920.

In the embodiment of our invention selected for illustration herein, the cleaning 45 part of the apparatus comprises a tank 1 divided into two compartments 2 and 3, each of the latter being equipped with conveyor means for carrying the cans through the apparatus. If so desired, the compartments

may be constructed as separate tank units 55 and joined end to end. Each conveyor comprises a moving can forwarder and a stationary can support rack and as the two conveyors are identical in construction, a description of one will apply to both. 60

The front forwarder 4 comprises a drive shaft 5 carrying a sprocket 6 engaging the links of a chain 7 passing over an idler sprocket 8 at the other end. The idler sprocket 8 is pivotally mounted between 65 arms 9 on a bracket 10 which is slidably supported on three rods 11 having telescoping engagement with a frame 12 the opposite end of which has U-shaped terminals 13 embracing sleeves 14 forming part of the bearings for the shaft 5.

As illustrated in Fig. 4, these bearings preferably comprise the outer sleeves 14, having flanges 15 suitably secured to the side walls of the tank, and supporting renewable 75 inner bearing sleeves 16 for the shaft 5. An end cap 17 may be removably secured to the outer sleeve 14 to protect the bearings.

The center one of the three rods 11 is preferably screw threaded and provided with 80 nuts 18 on opposite sides of the end cross member of the frame 12 through which the rod freely passes, and by means of which the longitudinal position of the bracket 10 may be adjustably positioned to properly tension 85 the chain 7.

The chain carries a plurality of regularly spaced bars 19 extending from side to side of the tank, each of the bars carrying U-shaped 90 clips 20, the arms of which project upwardly from the upper section of the forwarder for a purpose to be hereinafter described.

The ends of the bars are steadied and guided at the sides of the machine by guide shoes 21 suitably mounted on the frame 12, 95 as for instance, by attachment to upwardly projecting lugs 22 carried by the frame. A plurality of longitudinal strips or slats 23 overlie the forwarder and form a stationary rack to support the cans as they pass 100 through the machine.

The cans are laid in a horizontal position so that they roll sideways along the slats 23 being pushed along by contact with the upwardly projecting arms of the U-shaped 105 clips 20 on the forwarder. The ends of the slats 23 are bent downwardly as at 24 so that the cans after traveling the length of

the first conveyor will roll down by gravity onto the similarly arranged slats 23^a overlying the second or rear forwarder, the ends of the latter slats being inclined downwardly 5 as at 24^a to permit the cans to roll to the end of the tank where they may be delivered upon a suitable rack or drier as fragmentarily indicated at 25.

Any suitable power driven means for 10 actuating the forwarders may be employed. We have illustrated an electric motor 26, mounted on a suitable standard positioned laterally of the tank, and connected by a belt 27 and pulley 28 to a shaft 29 journaled in 15 an appropriate housing secured to the tank and carrying a pair of loose change speed pinions 30 and 31 adapted to be operatively engaged by a sliding clutch member 32 spliced on the shaft 29 and operable by a 20 yoke carried by a shifting rod 33 extending through the housing.

The pinions 30 and 31 are in operative engagement respectively with the gears 34 and 35, of different diameter, fixed on a 25 shaft 36. The latter shaft extends longitudinally of the tank and through a pair of casings 37 and 38 housing respectively the outer ends of the shaft 5 in each of the forwarders. Within each of the casings, the 30 shaft 36 carries a worm 39 (Fig. 4) in driving engagement with a worm gear 40 secured to the shaft 5, by which the respective forwarder chains are driven. The change speed mechanism is advantageous in adapting 35 the speed of the forwarders to the condition of the cans being washed.

Suitable means are provided for exposing the cans as they pass over each conveyor to the action of a number of powerful jets of 40 cleansing fluid in the front tank and to similar jets of rinsing and sterilizing fluid in the second tank. This means may be of the form described in our previous application Serial No. 409,172, or, as illustrated 45 herein, that set forth in the pending application Serial No. 515,497 filed Nov. 16th, 1921 and fully described therein.

Stated generally for present purposes, the 50 washing and rinsing jet mechanism comprises a pair of jet heads 41 oppositely positioned on the lateral walls of each of the compartments, and having inwardly directed orifices 41^a adapted to deliver a pressure spray of liquid from the opposed heads 55 forcibly upon the surfaces of the passing cans, thoroughly cleansing and rinsing them during their progress through the machine.

Each of the tank compartments preferably is part full of a suitable fluid which is 60 withdrawn through a pair of screens 42, successively positioned transversely of the tank at each end in sliding frames removable for cleaning, and through an intake pipe 43, by a suitable pump 44. From the latter 65 the fluid is delivered through a riser pipe 45

and a horizontal pipe 46 to one of each of the pairs of jet heads 41, and to the respective opposite head through an overhead pipe connection 47. The pump for the first compartment may be driven by a suitable connection of its shaft with the shaft of the motor 26, a similar motor and connection (not shown) being employed to drive the other pump for the rear or rinsing compartment.

The conveyors extend at a slight upward inclination, as clearly shown in the drawings, so that the fluid on the cans as it drains off will tend to fall back into the compartment from which it came, and the front compartment terminates in a partition wall 48 extending upwardly to a level considerably above the level of the liquid in the tank. Pivoted doors 49 are provided which may be readily swung out of the way by engagement with the cans as they pass through the machine. The doors are positioned to prevent the splashing of the sprayed liquid from one compartment to the other, and out the ends of the machine.

To facilitate cleaning or repairing the machine the top of the body is formed of a series of removable panels 50 upon removal of which, and of the slats 23 and 23^a, each of the forwarders may be swung up out of the machine as indicated in dotted lines in Fig. 2 by rotation of the frame 12 and forwarder around the axis of the drive shaft 5. The front ends of the conveyor frames 12 are movably supported by resting the extended end cross members upon brackets 51 attached to the side walls of the tank.

For the removal of vapor from the enclosed compartments, we have inclined the top wall at the delivering end of the machine upwardly to form a hood 52 to receive the vapor, and have associated therewith a suitable blower 53 adapted to withdraw the vapor and discharge it into a convenient flue (not shown). The hood may be provided with depending baffle plates 52^a to prevent the passage of liquid spray into the blower.

The level of the liquid in the tank compartments may be observed and maintained by means of laterally mounted boxes 54, having central partitions 55 of a height somewhat less than the box, and communicating as at 56 with the interior of the tank. The level of the tank liquid may be maintained to appear in the inner portions of the boxes, the excess overflowing the partition and passing out through the drain opening 56. The boxes may also serve for the introduction of washing compounds into the tank compartments.

The cylindrical containers ordinarily employed for handling bulk ice cream, and any other container or utensil having an approximately cylindrical body of sufficient

length to enable it to roll, will be carried through the device on the sloping racks 23 and 23^a in gentle contact with the clips 20 acting as followers. Rubbing between the 5 containers and the conveyors which rapidly wears the tin off the containers, is thus reduced to a minimum. It will also be apparent that any other shaped utensil such as a rectangular mold may be put through 10 the machine without more friction than it would be subjected to if drawn over any other sort of stationary track.

While we have illustrated and described in detail the preferred embodiment of our 15 invention, it should be clearly understood that the disclosure is merely for purposes of illustration and that many modifications and variations will naturally occur to those skilled in the art. We aim in the subjoined 20 claims to cover all such legitimate variations and modifications.

We claim as our invention:

1. In a device of the class described, a frame, a pair of shafts operatively mounted 25 at opposite ends of said frame, a forwarder belt operatively supported by said shafts, a series of spaced bars mounted transversely on said belt, a plurality of laterally spaced

stationary slats extending longitudinally of 30 said belt, said slats overlying said bars and being supported thereon, and a plurality of followers mounted on said bars adapted to project through and pass along the spaces between said slats by the operation of said belt.

2. In a device of the class described, a frame, a pair of shafts operatively mounted at opposite ends of said frame, a forwarder belt operatively supported by said shafts, a 40 series of spaced bars mounted transversely on said belt, a plurality of laterally spaced stationary slats extending longitudinally of said belt, said slats overlying said bars and being supported thereon, a plurality of followers mounted on said bars adapted to 45 project through and pass along the spaces between said slats, and a pair of stationary shoes mounted on said frame respectively underlying and supporting the ends of said bars as said bars move into supporting engagement with said slats by the operation of said belt.

In testimony whereof we have hereunto set out hands.

THEODORE L. VALERIUS.
OLAF LARSEN.
